US0D1071822S

(12) **United States Design Patent** (10) **Patent No.:** **US D1,071,822 S**
(45) **Date of Patent:** **** Apr. 22, 2025**

(54) **VEHICLE WHEEL**

(71) Applicant: **Anovia Wheels, LLC**, Wrightstown, WI (US)

(72) Inventor: **Alexander Martinez**, Appleton, WI (US)

(73) Assignee: **Anovia Wheels, LLC**, Wrightstown, WI (US)

(**) Term: **15 Years**

(21) Appl. No.: **29/916,652**

(22) Filed: **Nov. 14, 2023**

Related U.S. Application Data

(62) Division of application No. 29/764,265, filed on Dec. 29, 2020, now Pat. No. Des. 1,011,984.

(57) **CLAIM**

The ornamental design for a vehicle wheel, as shown and described.

DESCRIPTION

FIG. 1 is a perspective view of a vehicle wheel showing the claimed design;

FIG. 2 is a front elevation view of that seen in FIG. 1;

FIG. 3 is a further perspective view of that seen in FIG. 1; FIG. 4 is a perspective view of an alternate embodiment of a vehicle wheel showing the claimed design;

FIG. 5 is a front elevation view of that seen in FIG. 4; and, FIG. 6 is a further perspective view of that seen in FIG. 4. The broken lines in the drawings illustrate portions of the vehicle wheel that form no part of the claimed design.

1 Claim, 6 Drawing Sheets
